(57) **CLAIM**

(21) Appl. No.: **29/146,467**

The ornamental design for an enclosure for distribution
amplifier for computer and audio visual equipment, as
shown and described.

(22) Filed: **Aug. 10, 2001**

DESCRIPTION

(51) LOC (7) Cl. **14-02**
(52) U.S. Cl. **D14/432**; D13/147
(58) Field of Search D13/147, 154;
D14/265, 188, 432, 439, 356, 496, 217,
239; 439/638

FIG. 1 is a perspective view of an enclosure for distribution
amplifier for computer and audio visual equipment.

FIG. 2 is a top plan view thereof.

FIG. 3 is a right side elevational view thereof; and,

FIG. 4 is a front elevational view thereof.

The appearance of the bottom forms no part of the claimed
design.

The appearance of the back forms no part of the claimed
design.

The appearance of the left side forms no part of the claimed
design.
